UNITED STATES PATENT OFFICE.

BENEDICT T. GIBBS, JR., OF CHICAGO HEIGHTS, ILLINOIS, ASSIGNOR TO MORDEN FROG & CROSSING WORKS, OF CHICAGO, ILLINOIS, A CORPORATION OF ILLINOIS.

RAILROAD FROG PROTECTOR.

Application filed February 28, 1927. Serial No. 171,420.

This invention relates to railway track equipment and particularly to devices for filling in the triangular spaces at the junctions of angularly disposed rail members as, for instance, at the toes and heels of conventional railroad frogs and in connection with switch points, in which so many people have in the past caught their feet with resulting loss of their lives.

10 The object of the invention is to provide a metallic, permanent device of this class constructible with a minimum amount of labor, from a minimum number of parts, specifically two identical, comparatively simple 15 parts, easily and economically installable in place; the whole satisfactory in final operation.

The invention consists in a device attaining the foregoing and other objects and in 20 features and details hereafter more fully set forth in the specification and claims.

Referring to the drawings in which like numerals designate the same parts throughout the several views:

25 Figure 1 is a plan view of a conventional railroad frog equipped with two illustrations of the mechanism of this invention.

Figure 2 is a somewhat enlarged plan view of the frog at the left hand end of Figure 1, the head of one rail being broken away and some parts being shown in section.

Figure 3 is a side view taken on the line 3—3 of Figure 2.

35 Figure 4 is a transverse view taken on the line 4—4 of Figure 2.

Figure 5 is a perspective view of one of the two angle members entering into the construction of the device of this invention.

40 Figure 1 of the drawings shows a conventional railway frog 10, secured by spikes 12 to conventional ties 14 resting on the ground. Abutting the left or toe end 16 of this frog at lines 17 are two track rails 18 and 20, each secured in its proper conventional position at the end of the frog by a pair of fish plates 22 properly positioned across joints 17 and four bolts 24, 25, 26 and 27.

In accordance with standard practice, alternate bolts on each rail are inversely inserted, i. e., so that 24 and 26 have their heads 28 on a side of the rail opposite to the heads 29 of the other two bolts 25 and 27 in the same rail with the obvious result that the 55 nuts 32 of alternate bolts are on the oppo-

site side of the rail from the nuts upon the other two bolts. Also in accordance with standard railway track practice, bolts 24 in the two rails lie in a common plane across the two rails and are correspondingly positioned, i. e., point in the same direction; while the next pair of bolts 25 lie in a different parallel plane across the rails and point in the opposite direction. The same relationship exists between bolts 26, and between bolts 27.

It is conventional practice to make each of the connecting bolts just described with a non-circular portion 34 immediately adjacent to its head entering a corresponding non-circular perforation in the adjacent fish plate with the result that each bolt is held non-rotatively by the fish plate so engaged and it is, therefore, possible for the operator to turn up the nut 32 at the opposite end of that particular bolt.

The angular space 36 between the rails 18 and 20 terminating at about 38 in the toe of the frog 10 is an example of an angular space in track work in which people have in the past caught their feet, (particularly but not exclusively on the nuts and bolt heads lying within that space) which it is necessary to fill up to prevent such accidents. The device of this invention for this purpose is shown applied at this point.

Broadly stated, the mechanism comprises two angle irons 40 shown in detail in Figure 5, each having a horizontal top flange 42 and an adjacent vertical flange 44 so placed in angular space 36 that horizontal top flanges 42—42 sufficiently overlap as shown in Figure 4 to prevent a person's foot catching in the frog space. More in detail, each flange 44 is provided with two rectangular notches 46 sufficiently large to clear the two nuts 32, heretofore described, on the adjacent side of the rail. Each vertical flange 44 also has two inverted U-shape notches 48 having non-circular tops 50 adapted to receive and comparatively closely fit the non-circular portions 34 of bolts 24—27.

The outer or entrance portions of these U-shaped notches 48 are slightly wider than the minimum diameter of the non-circular parts 34 of the bolts so that by first loosening nuts 32 and partially withdrawing the bolts from their permanent position in the fish plate and then turning them 90° from the position shown in Figure 3, the non-

circular parts of the bolts may enter the U-shaped notches 48 as the angle member 40 is lowered to position as shown in the drawings, the final step in such operation being twisting the same bolts which are in these U-shaped notches through another 90° in either direction to bring the non-circular portion 34 to horizontal position, as shown in Figure 3, and then shoving the bolts into final position and tightening up nuts 32.

Each angle member 40 is in the process of manufacture provided with oppositely disposed, elongated end slots 52 and 54 formed in the horizontal flange 42 immediately adjacent to the vertical flange 44 with the result that the extreme end portions 56 of horizontal flange 42 may be selectively bent angularly downward, as shown in Figures 3 and 5, when and as desired by the operator.

When the operator has provided himself with two of the angle devices 40 of this invention, constructed as just described, he first loosens the four bolts 24-26 on each side of angular space 36, whose heads are within that space and then by manipulating the bolts as described places over said bolt-heads within the space 36 the two angular bars 40 with their flanges overlapping as shown particularly in Figure 4. There is sufficient play in the bolts and fish plates so the flanges 42 of identical angle bars 40 can overlap as shown. Having done this, the operator tightens up the nuts 32 which are on the sides of the adjacent rails and outside of the angular space 36, thereby firmly securing the device in position between the rails. Having done this, the operator takes a hammer and knocks down the two outer end portions 56 to the angular positions shown, thereby preventing a person's foot catching under the ends of flanges 42. When this has been done, the device is permanently located in operative position and prevents injury to people accidentally stepping within the angular space 36.

The angular members 40 are of such a length and have flanges 42 of such a width that the small space 62 at their most divergent ends is not sufficient for a passer-by to get his or her foot therein.

At the opposite or heel end of the frog 10 shown in the drawings are other rails 64 and 66 connected thereto by identically constructed fish plates and bolts, there being between these rails an angular space 68 which is filled in with the device of this invention in exactly the same manner as heretofore described in connection with the space 36.

A great advantage of this structure is that the inexpensive angular members 40 may be made in large quantities and interchangeably inserted in place, one overlapping the other, wherever the combinations of four bolts 24-27, arranged opposite each other as

shown, as is conventionally the practice, are used in attaching rails together over joints 17.

The angles 40 are made of sufficiently heavy metal so that the overlapping flanges 42 are strong enough to sustain the ordinary weights of persons stepping upon the assembled device.

As indicated in the opening statement, the invention is not limited to railway frogs but it may be applied to any angularly disposed track parts which present the described foot danger.

It is quite obvious that by equi-spacing the perforations 46 and 48, the angle bar 40 is made interchangeable on either side of the space to be protected where it would not be otherwise.

There is sufficient give to the bolt connections so that the flanges 42 may overlap as shown in Figure 4, notwithstanding the fact that the two bars 40 are identical and interchangeable.

Having thus described my invention, what I claim as new and desire to secure by Letters Patent is:

1. As an article of manufacture, for use as a foot guard, an angular member having a horizontal flange for engagement by a foot and a vertical flange for attachment to a rail, said vertical flange being provided with perforations for snugly engaging the rail bolts and with larger perforations for clearing the rail bolt heads.

2. As an article of manufacture, for use as a foot guard, an angular member having a horizontal flange for engagement by a foot and a vertical flange for attachment to a rail, said vertical flange being provided with perforations alternately engaging bolts on an adjacent rail and clearing intervening bolt heads on said rail.

3. As an article of manufacture, for use as a foot guard, an angular member having a horizontal flange for engagement by a foot and a vertical flange for attachment to a rail, said vertical flange being provided with equally spaced perforations alternately engaging bolts on an adjacent rail and clearing intervening bolt heads on said rail.

4. As an article of manufacture, for use as a foot guard, an angular member having a horizontal flange for engagement by a foot, a vertical flange for attachment to a rail, said horizontal flange having means disposed adjacent the junction of the flanges permitting the bending downward of an end portion of the horizontal flange for the purposes set forth.

5. As an article of manufacture, for use as a foot guard, an angular member having a horizontal flange for engagement by a foot, a vertical flange for attachment to a rail, said vertical flange being provided with perforations alternately engaging bolts on an

- adjacent rail and clearing intervening bolt heads on said rail, and means permitting the bending downward of an end portion of the horizontal flange for the purposes set forth.
5. 6. As an article of manufacture, for use as a foot guard, an angular member having a horizontal flange for engagement by a foot and a vertical flange for attachment to a rail, said vertical flange being provided with equally spaced perforations alternately engaging bolts on an adjacent rail and clearing intervening bolt nuts on said rail, and means permitting the bending downward of an end portion of the horizontal flange for the purposes set forth.
10. 7. As an article of manufacture, an angle member having a horizontal top flange 42 and a vertical flange 44, said device being provided with perforations 46 and 48 and notches 52 and 54, all arranged and disposed as shown and described.
15. 8. In the art described, in combination with two angularly disposed rails, each provided with a multiplicity of inversely inserted cross bolts correspondingly spaced apart along the respective rails and lying by two's in the same transverse planes across the rails, those in each cross plane being pointed in the same direction; a foot guard 20 in the space between said rails secured to said rails by said bolts, said guard comprising two reversely placed, identical angle bars having overlapping horizontal flanges and vertical flanges, each secured to respective adjacent rails by the bolts whose heads are in the space between the rails, there being in each of said vertical flanges notches clearing the nuts, on bolts, which are inside the space between the rails.
25. 9. An article of manufacture, for use as a foot guard, comprising an angular member having a horizontal flange for engagement by a foot and a vertical flange for attachment to a rail, said vertical flange being provided with perforations for snugly engaging bolts and with larger perforations for clearing bolt heads the end of the horizontal flange having a bendable tongue for the purposes set forth.
30. 10. An article manufactured for use as a foot guard, comprising an angular member including a vertical flange provided with perforations for snugly engaging bolts and larger perforations for clearing bolt heads, said perforations being alternately arranged and equi-spaced longitudinal of the vertical flange to permit the angular member to be installed on a rail on either side of the space to be protected, said horizontal flange having its opposite ends formed with free tongues normally lying in the plane of the horizontal flange but constructed and arranged to be bent downwardly for the purposes set forth.
35. 11. An article manufactured for use as a foot guard and attachable to the side of a rail comprising an angular member having a horizontal flange for engagement by a foot and a vertical flange for attachment to a rail, the end of the horizontal flange having a slot therein extending from the extreme end of the flange inwardly toward the other end of the flange to provide a bendable portion.

In witness whereof, I have hereunto subscribed my name.

BENEDICT T. GIBBS, JR.
